UNITED STATES PATENT OFFICE

2,076,495

FLASHLIGHT

Joseph William Bellamy, Ottawa, Ontario,
Canada

Application August 12, 1935, Serial No. 35,859

2 Claims. (Cl. 200—60)

This invention relates to a flashlight and more particularly to the switch and circuit thereof. The ordinary hand flashlight usually embodies a cylindrical body portion having a light lens and reflector encased at one end, one or more batteries in the body portion, a closure cap at the other end and a switch carried on the body portion intermediate the respective ends. Usually this switch embodies a member which is slidable particularly to the switch and circuit thereof. The ordinary hand flashlight usually embodies a cylindrical body portion having a light lens and reflector encased at one end, one or more batteries in the body portion, a closure cap at the other end and a switch carried on the body portion intermediate the respective ends. Usually this switch embodies a member which is slidable 5 and designed to be moved by the finger or thumb of the operator. This construction of a switch may only be used for lighting purposes and cannot be used for testing fuse plugs, lights, circuits or other electrical apparatus or hook-ups such as 10 are commonly required to be accomplished by troubleshooters when working on electric circuits or fixtures. Furthermore, I have found that a great many of such switches become loose after a reasonable amount of reciprocation of the movable 15 member and, if the flashlight falls or is jarred, the circuit contact is often broken. My construction, as herein set forth, overcomes these undesirable features. Furthermore with the switch 20 which I provide, a rolling action of the body portion on a flat surface will move the switch arm to inoperative position.

With the foregoing and other objects in view, as will appear as the description proceeds, the invention consists of the novel construction, combination and arrangement of co-operating elements as hereinafter more specifically set forth, claimed and shown in the accompanying drawing forming a part of the present application, in which:—

35 Fig. 1 is a perspective view of the preferred embodiment of my invention.

Fig. 2 is an end plan view of my switch cap, looking toward the inner face thereof.

Fig. 3 is a longitudinal sectional view taken on 40 line 3—3 of Fig. 2.

Fig. 4 is a longitudinal elevational view of the switch end of the flashlight, showing the mode of testing a fuse plug.

Fig. 5 is a schematic view of the switch circuit. 45 Like numerals of reference designate corresponding parts throughout the different views.

The principle of my invention disclosed in this application is primarily in regard to the switch construction as hereinafter disclosed. But, to 50 illustrate the switch and its operative relationship in the complete flashlight construction, I have shown a body portion 6 of cylindrical form, in which may be carried a light, lens, reflector and any suitable holding means therefor at the 55 end 7 of the body portion 6. One or more dry

cell batteries 8 may be positioned in the body portion 6 in proper circuit arrangement. Various modifications may be made in the part of the flashlight so far described and I do not wish to claim any specific invention pertaining thereto, other than these respective elements to complete the circuit in which the hereinafter switch construction forms a part.

The opposite end of the body portion 6 may be threaded or provided in any other suitable way 10 with a means for engaging and retaining my switch cap hereinafter referred to. The body portion of my switch cap is preferably made of stamped or suitably formed insulation material and comprises a disc-shaped body portion 9, 15 having the periphery of its outer end flanged outwardly thereof as at 10. The inner end of the disc-shaped body portion 9 is provided with an inwardly directed cylindrical portion 11. Supported inwardly from this cylindrical portion 11, 20 I provide an engagement portion 12 of conductive material and formed in such a manner as to be easily engaged with the threading or other engagement means on the adjacent end of the body portion 6. A conductor pin 13 is carried 25 through the cylindrical portion 11. One end of this conductor pin 13 is in fixed contact with the engagement portion 12. The other end of the conductor pin 13 is preferably headed and is held in the path of travel of a switch member 30 hereinafter referred to.

Centrally positioned relative to the inner face of the portion 9, I provide a helical spring 14, one 35 end of which is of spiral formation and engaged to the inner face of the disc-shaped body portion 9 by means of the clip 15 and the screw 16.

The screw 16 also extends through an opening in the inner end of the switch arm 17. An arcual slot 18 is formed between the meeting portions of the disc-shaped body portion 9 and the inwardly directed cylindrical portion 11, through which slot the free end of the switch arm 17 protrudes. The outer end of the switch arm 17 may be bent laterally and provided with a serrated or any other suitably formed finger grip. Referring to Fig. 2, 40 I show three positions to which the switch arm 17 may be moved. When in the position 17a, it is in normally opened position and the circuit hereinafter referred to is positively broken. When in the position 17b, the circuit is closed through the 45 switch arm 17 being in contact with the headed end of the conductor pin 13. When in the position 17c, the circuit hereinafter referred to (also shown in Fig. 4) is in open position, but the switch arm is in such position that a fuse 19, light or 50

contact points may have their ends positioned to engage respectively the switch arm 17 and the body portion 6. When an article to be tested is thus positioned relative to these respective parts, the circuit will be completed and the flashlight light (not shown) will be energized, thus intimating to the operator that the fuse 18 or other article being tested is in proper functioning order.

10 I wish to herein draw attention to the fact that, upon the flashlight being rolled on a flat surface, the protruding end of the switch arm 17 will be pressed to the position as shown at 17a and thus make a positive disconnection of the circuit. I 15 further want to direct the attention of those skilled in the art to the fact that the switch arm 17 (as engaged under the screw 16) has a double resistance movement partially through the engagement by the screw 16 and partially by the re- 20 slient engagement under the spring 14 when in positively broken position or in circuit closed position.

25 In the illustration and in the specifications hereinbefore set forth, I have disclosed a flashlight embodying a cylindrical body portion 6. This body portion may be rectangular shaped in cross section or in any other desired shape and the same principle of switch may be used in combination therewith by having certain minor changes 30 in configuration to facilitate proper arrange-

ment of the respective parts and operations thereof in a like manner to that hereinbefore described.

The foregoing specification and annexed drawing disclosed the preferred embodiment of my invention, but it is to be understood that minor changes may be resorted to in the commercial adaptation of my invention without departing from the scope of the invention as hereinafter claimed.

What I claim as new is:

1. In a portable flashlight, a switch cap comprising a plug of insulating material formed with a recess on its inner end and an annular groove adjacent its outer end, said grooved portion being formed with a slot connecting said portion with 15 said recess, a metallic collar carried on the inner end of said plug and fitting the body of the flashlight, a spring contact housed in said recess, and secured to said plug, a switch arm connected to said spring contact and pivotally mounted on said plug in said recess and projecting thru said slot into the grooved portion of said plug and a contact connected to said metallic collar engageable by said switch arm.

2. In a portable flashlight according to claim 1, wherein said switch arm is provided with a finger grip which is securely housed in said grooved portion when said switch arm is in inoperative position.

JOSEPH WILLIAM BELLAMY. 3
